UNITED STATES PATENT OFFICE.

WILLIAM E. RIECKEN, OF GLENDALE, NEW YORK, ASSIGNOR TO WESTERN ELECTRIC COMPANY, INCORPORATED, OF NEW YORK, N. Y., A CORPORATION OF NEW YORK.

MOISTUREPROOF RECEPTACLE.

1,426,776.

Specification of Letters Patent. Patented Aug. 22, 1922.

Application filed December 27, 1918. Serial No. 268,542.

To all whom it may concern:

Be it known that I, WILLIAM E. RIECKEN, a citizen of the United States, residing at Glendale, in the county of Queens and State 5 of New York, have invented certain new and useful Improvements in Moistureproof Receptacles, of which the following is a full, clear, concise, and exact description.

This invention relates to moistureproof 10 receptacles and in particular to the means employed for securing the lid or cover of such a receptacle.

In apparatus used in various types of field telephone sets and also sets intended 15 for use in damp places, it is often necessary that the apparatus, in order to function properly, be protected from moisture. However, it is also often necessary to mount certain of the apparatus so that it is easily 20 and quickly available for the purpose of adjustment or replacing. It is therefore the common practice to arrange the apparatus in such sets so that the apparatus which requires attention is mounted together 25 in a certain portion of the box and a lid or cover is provided to permit access, this lid or cover being provided with gaskets to prevent the entrance of moisture. If the covers or lids are not secured in place 30 by means of hinges, there is danger of these parts becoming misplaced and lost; but with the type of hinge used heretofore, the gaskets are quickly mutilated and lose their effectiveness in preventing the ingress of 35 moisture.

It is therefore the object of the present invention to provide a moistureproof receptacle in which means is provided to permit the cover being drawn in place and with 40 equal pressure on all sides, thereby permitting the gaskets to function properly in preventing the entrance of moisture and without danger of becoming damaged, due to frequent use. This object is obtained by 45 providing a receptacle equipped with suitable gaskets and an adjustable hinge having a loose pin or pintle and leaves provided with oblong openings on which the pin is journaled, these slots being arranged 50 in the direction in which pressure is to be applied. The various features of this invention may be more clearly understood by reference to the accompanying drawing in which Fig. 1 is a view partly in section 55 showing a receptacle provided with a hinge

adapted to permit movement in a vertical direction; Fig. 2 is a plan view of the type of hinge employed in Fig. 1; and Fig. 3 is a view of a somewhat similar receptacle in which the hinge is necessarily modified 60 to permit movement in a horizontal direction.

Referring now to Figs. 1 and 2, there is shown an apparatus casing or box 5 provided with a cover 6, in the lower edge of 65 which is inserted a gasket 7 of soft rubber or similar material. Secured to these parts by means of the screws 8—8 is an adjustable hinge comprising a pair of flat leaves 9—9 and a bearing pin or pintle 10. The leaves 70 9—9 are made in the usual manner by folding a piece of flat stock back upon itself and providing the necessary supports for the bearing pin. These leaves, the bearing 75 portions of which intermesh with each other, differ, however, from the leaves of the common type of hinge in that the bearing supports are made oblong, as shown at 11—11, thereby permitting a right line movement in a direction perpendicular to 80 the axis or pin of the hinge, as well as a rotary movement obtained from the ordinary hinge construction. In order to draw the cover toward the casing and thereby obtain a moistureproof joint, a clamping 85 means is provided consisting of a screw portion 12 secured to the cover and a shoulder portion 13 secured to the box. By means of the wing nut 14, which upon turning, bears against the shoulder plate 13, it 90 95 is possible to draw the two parts together, thereby compressing the gasket 7 uniformly on all sides, since the oblong portions 11—11 allow sufficient play on the hinge to prevent binding. While only one hinge and one clamp are shown on the drawing, it is of course to be understood that one or more hinges may be employed and it will be advisable to use at least two clamps mounted 100 on opposite sides of the cover.

In the arrangement shown in Fig. 3, there is illustrated an enclosing casing or box 20 equipped with a door or lid 21 which is secured in place by means of a hinge employing the same principle as that described 105 above, but in this case the oblong portions of the hinge leaves are formed so as to permit movement in a direction perpendicular to the plane of the hinge leaves 23—23. A gasket 24 of soft rubber or other easily com- 110

pressible material is fitted as shown in the inner edges of the lid 21, and a clamp consisting of a screw member 25, shoulder plate 26 and wing nut 27 is provided to draw the lid securely toward the casing, thereby compressing the gasket 24 and insuring the desired moisture-proof joint.

By means of the construction embodying this invention, a receptacle is provided to which a cover or lid may be hinged in such a way as to permit the necessary movement for clamping the parts together to obtain a moisture-proof joint.

What is claimed is:

15. 1. A receptacle comprising a casing, a closure therefor, compressible means positioned between said casing and closure, means for compressing said compressible means, and a hinge member loosely connecting the casing and closure, said hinge member being arranged to permit right line movement in a direction perpendicular to its axis.
20. 2. A receptacle comprising a casing, a closure therefor, compressible means positioned between said casing and closure, means for compressing said compressible means, a hinge member loosely connecting the casing and closure, said hinge member comprising a pair of intermeshing leaf members, one of which is provided with an oblong opening, and a loose pintle connecting said casing and closure to permit right line movement.
25. 3. A receptacle comprising a casing, a closure therefor, compressible means positioned between said casing and closure, means for compressing said compressible means, a hinge member loosely connecting the casing and closure, said hinge member comprising a pair of intermeshing leaf members, each
30. 40. of which is provided with an oblong open-

ing, and a loose pintle connecting said casing and closure to permit right line movement.

4. A receptacle comprising a casing, a closure therefor, compressible means positioned between said casing and closure, means for compressing said casing and closure against said compressible means, and a hinge member connecting said casing and closure, said hinge member being arranged to permit right line movement in a direction perpendicular to its axis.

5. A receptacle comprising a casing, a closure therefor, compressible means positioned between said casing and closure, means for compressing said casing and closure against said compressible means, and a hinged member connecting said casing and closure, said hinged member being adapted to permit movement between said casing and closure in a right line direction and to prevent movement in a transverse direction.

6. A receptacle comprising a casing, a closure therefor, compressible means positioned between said casing and closure, means for compressing said compressible means, a hinged member loosely connecting the casing and closure, said hinged member comprising a pair of intermeshing leaf members, one of which is provided with an oblong opening, and a loose pintle having a diameter substantially equal to the width of said oblong opening connecting said casing and closure, to permit right line movement and to prevent transverse movement.

In witness whereof, I hereunto subscribe my name this 24th day of December, A. D. 1918.

WILLIAM E. RIECKEN,
